UNITED STATES PATENT OFFICE

EDWARD F. J. TIPPET, OF NEW YORK, N. Y., ASSIGNEE TO IRVING IRON WORKS COMPANY, A CORPORATION OF NEW YORK

CURVED GRATING

Application filed February 18, 1931. Serial No. 516,538.

This invention relates generally to continuous grating structures of the class shown in U. S. Patent to W. A. Van Hoffen No. 1,629,134, dated May 17, 1927, and also in 5 Patents Nos. 1,732,902 and 1,733,903 to P. L. Price, No. 1,733,923 to J. A. Voskamp, and No. 1,733,965 to W. E. Irving, all dated Oct. 29, 1929, but more specifically said present invention comprises certain modifications of 10 such gratings which will preserve the effect of continuity of a uniform mesh when individual sections or panels, to be connected together or to standard sections or panels, are bent or curved laterally to enable the entire, continuous structure so produced to be deflected from a straight line to any desired 15 extent necessary to carry it around corners or bends such as frequently occur in runways or highways.

20 Gratings of the class referred to are now being used for armoring the pavements of bridges, and are being seriously considered for use in armoring the surfaces of concrete highway pavements. In the first of the above 25 outlined uses it is sometimes necessary to extend the grating around bends in connecting the bridge floor with its approaches, and in the use on highways it will, of course, be necessary to maintain substantial continuity 30 around many curves and corners.

Much effort has heretofore been expended 35 on attempts to design a grating structure which will solve the curve and corner problem in a manner that will enable standard unit panels to be economically manufactured with existing plant equipment, and then be readily connected together on the job by workmen familiar only with methods now used for connecting straight panels of this 40 type. Any formation of curved or bent joints between panels, so that a portion of a polygonal perimeter approaching a curve in outline may be produced by so connecting a series of straight panels, necessarily introduces many complications in shop practice 45 and installation methods, and does not produce satisfactory results as to durability and appearance of continuity. Also the use 50 of any arcs of curvature of considerable extent in the body of a panel requires the care-

ful shaping of a large number of bars each to an arc of different radius, and a progressive elongation of the crimp in successive bent strips, and this in turn requires skill, special machinery and dies and much time, 55 and also involves peculiar difficulties in properly spacing the rivet holes.

I have found, however, that all of these and some other difficulties can be overcome by bending the standard panels at or near 60 their middle points, or at some other definitely located points which will be found uniformly spaced apart when a number of such panels have been connected end to end to form an approximately curved outline, and 65 thus retaining unchanged the present forms of joints or splices between panel ends. Also this bending of the panel can be done without destroying the parallelism of the longitudinal bars if the locus of all such bends in 70 laterally adjacent panels is confined approximately to a straight line extending transversely of the grating and preferably bisecting the angle of bend in each panel. The 75 strips of metal connecting and spacing apart these bent bars may be arranged in the usual manner, beginning at each end of each panel and meeting at the bend, where, if said connecting strips are of the crimped, longitudinally extending order, some may continue in 80 integral form around said bend, and the rest may each be separated into two parts by such 85 relatively arranged small gaps that inset strips, continuing the standard mesh outline, may be inserted and fastened to the adjacent longer strips and straight bars by rivets or 90 other means in the usual way so as to leave no loose ends, and this with no very noticeable variation from the standard spacing between rivet, bolt or welded joint centers. 90

Various arrangements of such inset strips 95 may be devised to meet the requirements of different job-layouts, and it is impossible to define any set of absolute or relative dimensions which would apply to all embodiments of this invention, but in the accompanying drawings I have illustrated forms of bent grating panels showing typical specimen of filling strip arrangements accommodating the class of grating and angle of bend there 100

represented in the best manner now known to me. In said drawings:

Fig. 1 is a plan view of a bent grating panel in which some of the crimped strips 5 are continuous, others left with short open gaps, and others connected together by short inset pieces.

Fig. 2 is a similar view of a modification in which all pairs of crimped strips are connected by short inset pieces, and

Fig. 3 is a diagrammatic plan, on smaller scale, of an armored highway pavement embodying my invention and extending around a curve in the road.

Throughout the drawings like reference characters indicate like parts. Referring to Fig. 1, the bent panel X, there shown, is composed of parallel bars numbered 1 to 5 in sets of five which are spaced apart and connected together throughout all or major portions of their lengths by bent strips numbered 11 to 15, also arranged in corresponding sets of five and each fastened to adjacent bars at all points of contact therewith by similar standard rivets 10, 10, in the usual way. The bars are all bent at the same angle with the locus of the bends extending along straight dotted line 7-7. The bent strips have uniform crimps throughout except that the crimp in continuous strip 11, which is in this locus, is slightly deformed to correspond to the bends in the bars. The registry of the standard crimps in adjacent strips one with another necessitates cutting the remaining strips 12 to 15 of each set in the neighborhood of the bends in the adjacent bars and leaving gaps between the adjacent ends so formed. The gaps 6, 6, so left in strips 12 and 13 are so short that it is not necessary to fill them to preserve the general effect of continuity of mesh, but the gaps between the adjacent ends of strips 14 and 15, being nearly equal to one mesh length, are preferably bridged across by inset strips 24, 25, having substantially the standard crimp outline and forming lap joints 18, 18, with the longer strips, which joints are held together and to bar 5 by special rivets 40, 40, long enough to include the 5-ply fastening so resulting. The two-ply fastening between each inset strip 24 and bar 4 is formed by a special short rivet 20.

The ends of each panel above described are formed to comply with any desired uniform system of splicing to enable them to be readily connected together or to standard straight panels of the same system and so produce a curved runway, or pavement armoring, as indicated in Fig. 3, where X or Y indicate bent panels, 9, 9, straight panels, 8, 8, the splice loci between panels, and 21 the concrete pavement. The particular panel ends for forming these spliced joints here shown are those described in the previously mentioned patent to Van Hoffen, No. 1,629, 134, but any other desired form of splice

might be substituted for this particular variety.

Referring to Fig. 2, the bent panel Y there shown is composed of parallel bars numbered 31 to 35 in sets of five, which bars are also spaced apart and connected together throughout major portions of their lengths by bent strips numbered 41 to 45, arranged in corresponding sets of five, each strip being fastened to adjacent bars at all points of contact therewith by standard rivets 10, 10, in the usual way. These bars, as before, are all bent at the same angle, with the locus of the bends extending along straight dotted line 7-7, which bisects the angle formed by each bent bar. The bent strips have uniform crimps and extend from either end of the panel nearly to the bends in their associated bars, but gaps are left at said bends so that the bent strips are really in pairs. The first three pairs 41, 41; 42, 42; and 43, 43, are of equal length and have a gap of at least one mesh length between the members of the pair. The next two pairs, 44 and 45, are half a mesh length longer than the first three. Considering each set of five strips the adjacent ends of each pair are separated by intervening distances substantially as follows, counting from the concave side of the bent panel; 41, 41, a little more than one mesh-length; 42, 42 and 43, 43, a little less than two-mesh lengths, and 44, 44, and 45, 45, by about one mesh-length. The spaces so left are preferably filled by short inset bent strips having approximately the standard crimp outline and proper lengths as follows: 51, a little more than one mesh-length; 52, and 53 a little less than two mesh-lengths, and 54 and 55 about one mesh-length. These inset strips are slightly deformed as may be necessary to fit them in between the bent bars on either side, and between the longer bent strips at either end, as shown. Preferably they are all fastened to the adjacent bars where in direct contact with the latter by standard rivets 10 or 10a forming the standard 3-ply fastenings between bars and strips and by short rivets 20 forming the 2-ply fastenings 17, 17. Strips 42, 52 and 43, 53, are connected by lap joints forming components of the 4-ply fastenings 19, 19, held together by long rivets 30, 30. The connections between strips 41 and 51, 44 and 54, and 45 and 55 are butt joints employing the extra rivets 10a and 20, but these details of butt and overlap joints may be varied to suit special cases, according to whatever method will most nearly approximate the desired effect of continuity of a uniform mesh.

The reason why the first strip 41 of each set of five in panel Y is not made continuous like strip 11, in panel X, is because the space between the crimps in 41 on either side of the grating bend must be greater than can be filled in by one deformed standard crimp in a continuous strip, as is done in panel X. This

wider separation is necessary to avoid too great a shortening of the insets 52 and 53 of two mesh-length which, even in the present arrangement, must have some of their crimp sections considerably distorted to fit into the spaces left for them.

An important advantage of the invention is the fewness of the departures from standard grating practice required for its various embodiments. The straight bars can easily all be bent to the same angle, and the rivet hole spacing in them is nearly all of standard length. In Fig. 1 such spacing in bars 1, 1, is unchanged. The remaining bars have modified hole spacing only midway of the length of each and, as these spacings are symmetrical with reference to the middle of each bar, the punching can be done in the regular way from each end of the strip toward the middle, or the one or two non-uniform spaces can be clearly marked on each bar and then the punching can be done as usual by running the bar through the punch from end to end, using the standard spacing 25 gauge, except at the middle, where one or two holes will be punched according to said markings. The longer bent strips 11 to 15 are all crimped in the regular way on one set of dies, and the only special crimp needed is for 30 the insets 24 and 25. The arrangement shown in Fig. 2 presents the same advantages but to a slightly less degree. When either type of bent panel is being used they can be connected together by the same method used 35 in connecting straight panels of the same end-construction.

Various changes in the details of construction here shown could be made without departing from the underlying principles of the invention. Different angles of deflection in the parallel bars might require minor modifications in the rivet spacings at the bend, and in the outline of the inset strips, and some of the latter might be dispensed with 40 altogether, or other filling elements used for bridging the short gaps between the longer crimped strips. In all cases, however, the effect of substantial continuity of mesh would be retained, and also the rigidity of structure 45 and simplicity of manufacture.

In order that additional lines of grating panels may be fastened to the upper edges of those illustrated in Figs. 1 and 2, bolts 22 are shown as the fastening means for the 50 outside bars 3 and 32, instead of rivets. The panels for filling in the inner portions of a broad roadway would be shipped without any bars along their concave sides and so could be bolted directly to the panels shown here, after removing bolts 22, 22, assembling the 55 panels and replacing the bolts.

Having described my invention, I claim:

1. A grating for use in flooring and pavements which comprises, in combination, a 60 plurality of parallel bars each bent through

a common angle with the common locus of said bends extending transversely of said bars, a series of uniformly bent strips located between and serving to connect together said bars along the major portions of their straight sections and a series of short bent strips located between and serving to connect together certain of the bent sections of said bars, said inserted short strips being bent into a shape substantially the same as that of the crimps in said uniformly bent strips. 70

2. A combination such as defined in claim 1 in which said short strips are bent into forms approximating the crimps in the said uniformly bent strips and have their ends placed against the adjacent ends of certain of the latter; whereby a general effect of uniformity and continuity of mesh throughout the grating structure is produced. 80

3. A grating for use in floorings and pavements which comprises, in combination, a plurality of parallel bars each bent through a common angle with the locus of said bends extending transversely of said bars in a substantially straight line, two series of uniformly crimped strips located between and serving to connect together said bars along major portions of their straight sections but having their adjacent ends spaced apart by distances sufficient to form approximately 90 one to two mesh-lengths, and a series of short crimped strips inserted between said adjacent ends of all the longer strips and between said bars, and connected to the latter, said inserted short strips having crimp outlines substantially the same as those of said longer strips. 95

4. A combination such as defined in claim 3 in which said inserted short strips are arranged in recurrent sets of five, the members of each set having different lengths substantially as follows, counting from the end of each set nearer the inside of the grating bend; one of one mesh-length, two of two-mesh length, and two of one mesh-length, with the 100 crimp outlines slightly distorted to adjust them to the bends in the straight bars and the spaces to be filled between ends of said longer strips. 110

5. A laterally bent grating for use in floorings and pavements which comprises, in combination, a plurality of parallel bars each bent through a common angle with the locus of said bends extending transversely of said bars in a substantially straight line, and a plurality of relatively long, uniformly crimped strips located between and serving to connect together said bars along major portions of the straight sections of some thereof and along all portions of the remaining bars, and a series of short strips bent approximately to the uniform crimp outline of said above mentioned long strips and inserted between the adjacent ends of those which are the more widely spaced apart, said short 120 125 130

strips being fastened to the bars adjacent thereto.

6. A metallic armoring for a curved section of a highway comprising, in combination, a series of grating panels spliced together at their abutting ends, each of said panels being bent laterally at an intermediate point in its length, and being formed of a plurality of parallel bars, each bent to the same degree with the locus of all said bends extending transversely of said panel on substantially a straight line, and a plurality of strips having substantially uniform successive crimps located between and fastened to said bars at all points of contact therewith; whereby said structure is given a polygonal outline approximating that of an arc of a circle.

7. As a new article of manufacture, a laterally bent panel of grating which comprises, in combination, a plurality of parallel bars each bent to the same degree with the locus of all said bends extending transversely of said panel in a substantially straight line, and a plurality of strips of substantially uniform outlines connecting together and spacing apart said bars so that the visual effect of the assembly is that of a substantially uniform grating mesh throughout the panel.

8. As a new article of manufacture, a laterally bent panel of grating which comprises, in combination, a plurality of parallel bars each bent to the same degree with the locus of all said bends extending transversely of said panel in a substantially straight line, and a plurality of strips of substantially uniform outlines connecting together and spacing apart said bars, said strips being arranged in one continuous standard pattern from each end of the panel to the locus of the bend therein and a minor number of short strips of approximately the same outlines being there inset to piece out spaces there left between said first mentioned strips, and to bridge over such space with substantially the said standard pattern.

Signed at Long Island City, in the county of Queens and State of New York this 16th, day of February, A. D. 1931.

EDWARD F. J. TIPPEL.
